UNITED STATES PATENT OFFICE.

FERDINAND WESEL, OF NEW YORK, N. Y.

MACHINE FOR SHAVING ELECTROTYPES, STEREOTYPES, &c.

SPECIFICATION forming part of Letters Patent No. 609,643, dated August 23, 1898.

Application filed November 5, 1897. Serial No. 657,469. (No model.)

To all whom it may concern:

Be it known that I, FERDINAND WESEL, a citizen of the United States, residing at New York, (Brooklyn,) in the county of Kings and State of New York, have invented certain new and useful Improvements in Machines for Shaving Electrotypers, Stereotypes, &c., of which the following is a specification.

This invention relates to certain improvements in machines for shaving off stereotype and electrotype plates and blocks either "pica high," "block high," or "type high," or other height, as required, by a simple, quick, and effective adjustment of the knife-head of the machine in such a manner that the accurate shaving of a plate or block is accomplished so as to avoid any tilting of the plate or block when the knife arrives at the end of its cut; and the invention consists of a machine for shaving stereotypes and electrotypers the knife-head of which can be quickly adjusted by suitable gages so as to shave either pica high, block high, or type high, as required, said knife-head being provided with adjustable spring-cushioned rollers at some distance from the shaving-knife and by which the plate or block is held in position against tilting during the cutting action of the knife and when the same arrives at the end of its cut; as will be fully described hereinafter, and finally pointed out in the claims.

In the accompanying drawings, Figure 1 represents a side elevation of my improved stereotype-shaving machine. Fig. 2 is a front elevation of the adjustable knife-block, showing the mechanism for setting the same. Figs. 3 and 4 are vertical transverse sections, respectively, on lines 3 3 and 4 4, Fig. 5. Fig. 5 is a horizontal section on line 5 5, Fig. 3. Fig. 6 is a vertical transverse section, drawn on a larger scale, showing the knife in the act of shaving off a stereotype-plate and the spring-actuated plate-holding roller at the end of the same; and Figs. 7, 8, and 9 are top, side, and sectional views (the latter on line 9 9, Fig. 7) of one of the gages for permitting the adjustment of the knife-head and knife so as to shave either pica high, block high, or type high.

Similar letters of reference indicate corresponding parts.

Referring to the drawings, A represents the supporting-frame of my improved machine for shaving stereotypes, electrotypers, or other matter. On the frame A is supported a bed-plate B, which is of oblong shape and large enough to support the different sizes of stereotypes to be shaved. The end of the stereotype-plate abuts against a transverse abutment or work-rest b at the front end of the bed-plate B, whereby it is held in position during the shaving action of the cutting-knife. The shavings are collected in a suitable box or receptacle beyond the work-rest b. (Not shown in the drawings.)

Along guide-rails d at the sides of the bed-plate is guided the transverse support D for the knife-head, said support being provided with grooves d', so as to fit on the guide-rail d. The support D is provided with recesses d', in which are guided the lugs e of the knife-head E. The knife-head E is guided along the inclined faces of the transverse support D by means of ways e', that are arranged at both sides of the support and attached thereto by suitable screws, as shown in Fig. 5. The shaving-knife E' is placed against a raised portion of the knife-head E and attached to the same by means of headed screws e'', which pass through slots e' in the shaving-knife. The upper end of the shaving-knife E' is acted upon by adjusting-screws f, which turn in lugs f' on the face of the knife-head E, so as to readjust the knife on the knife-head after sharpening the same to the exact position required. The knife-head, together with the knife, can be quickly raised or lowered by means of screw-spindles F, which pass through the lugs e at the rear of the knife-head E and which are operated by means of gear-wheels F' at their upper ends, said screw-spindles being retained in bearings of the transverse support D by means of shoulders on the spindle. Between the gear-wheels F' at the upper end of the screw-spindles F is interposed a pinion F², which is mounted on a stationary short pinion-shaft F³, the hub of the pinion being connected with a large hand-wheel F⁴, having two handles F⁴ for conveniently turning the hand-wheel in either direction.

The circumference of the hand-wheel F⁴ is graduated so as to permit the adjustment of the knife-head in connection with the station-

- ary pointer or index I, attached to the central front part of the knife-head, said index being curved in backward direction, so that its point is in front of the hand-wheel F³. By 5 turning the hand-wheel in one or the other direction the knife-head is raised or lowered on the inclined face of the transverse support D, according to the thickness of the plate or block which is to be shaved. At both sides 10 of the support D, at the corners of the same, is arranged an axially-adjustable triple gage G, which is provided with three lugs, of which two, G' G², are for pica and type high adjustment and are arranged in line with each other 15 and the other lug, G³, for block-high adjustment, which is arranged at right angles to the two others, as shown clearly in Fig. 7. The triple adjusting-gage G, with its three blocks, is swiveled to a headed pivot-screw g, Figs. 7, 20 8, and 9, so that the gage can be readily turned on the said pivot, so as to present any one of its three lugs to the laterally-extending stop-lugs g', Fig. 2, at the upper end of the knife-head E. When it is desired to adjust the 25 knife-head and its knife to the required thickness for pica or block, the knife-head is raised by the hand-wheel and its intermediate transmitting-gearing sufficiently so as to permit the turning of the gages so that the lug of the 30 proper size is presented, after which the knife-head is moved by turning the hand-wheel F³ in opposite direction in contact with the respective lug, so that the knife-head is thereby directly and quickly adjusted into the required 35 position. When, for instance, the knife-head is to be adjusted to type-high position, the lug corresponding to this position is placed under the lug g', and thereby the knife-head and its knife adjusted to the stereotype-block of that height. When the 40 knife is to be adjusted to block high, the lug corresponding to this position is placed under the stop-lug g', so that the knife is set directly for shaving a stereotype-block block-high. When, however, the knife is to be set 45 for pica high, the smallest lug is placed below the stop-lug, so that the knife is in its lowermost position and arranged for shaving stereotype-plates pica high. 50 The triple gage G may be provided with a spring-actuated pin g², that is provided with a pointed end, so as to take into small conical depressions g³, arranged in the upper corners of the support D, equidistantly from the pivot-pin g, so that the gage is held in proper position by the locking action of the pin. 55 The adjustment of the knife-head by the gearing described, in connection with the triple gage, permits the quick and reliable adjustment of the knife-head to the blocks or plates to be shaved and produces the gradual shaving of the back of the plate to the required thickness until the stop-gages arrive 60 on their respective lugs of the gage and terminate thereby the shaving action on the plate, for the reason that the same is reduced 65

to the required thickness by the successive shaving action of the knife as set by the hand-wheel and intermediate gearing and screw-spindles of the knife-head.

When the size of the lugs G' G² G³ of the gages differs from the thickness of the block to be produced, then the hand-wheel is turned for a certain number of graduations, as indicated by the pointer I.

The knife-head E is provided, in addition to the rear lugs at its rear sides, with boxes h, in which are guided the shanks h' of bearings h², in which the transverse rollers H are supported. The shanks of the bearings are 80 guided in the lower ends of the guide-boxes and provided with interiorly-threaded sockets, which are engaged by spindles h³, threaded at their lower ends so as to engage said sockets, said spindles passing through the closed 85 top of the guide-boxes h and being provided with shoulders h⁴ above the same. The upper squared ends of the spindles h³ extend through openings in the support D, so that they can be readily taken hold of by a suitable tool for 90 adjusting the roller-bearings higher or lower relatively to the guide-box, as required for the position of the roller relatively to the knife-head. Between the shanks of each of the roller-bearings and the upper end of the 95 guide-box h is interposed a helical spring h⁵, which exerts a cushioning action on the roller H. The roller projects in a plane below that of the edge of the shaving-knife, in which position the collar h⁴ abuts against the upper 100 closed end of the guide-box h, as shown in Fig. 4. During the motion of the knife over the back of the stereotype plate or block the roller is pressed upwardly against the springs, and is thereby pressed tightly on the plate 105 so as to hold the same in position and prevent it from shifting laterally or from tilting when the knife arrives near the end of the stereotype, which in the former construction of 110 shaving-machines has been a very objectionable feature. By means of the roller the shaving action on the plate is made steady and reliable, the plate held throughout the shaving action of the knife firmly in position on the bed-plate of the machine, and injury 115 to the type avoided when the knife arrives near the end of the plate, as any tilting of the plate is prevented by the pressure of the roller on the back of the stereotype plate or block. The roller is an important and valuable 120 improvement in shaving-machines of this class, as it is adjusted with the knife-head, and it remains in a proper relative position to the knife-head, it requiring only adjustment in the guide-boxes, when, after the 125 shaving-knife is sharpened or its position changed on the face of the knife-head, the corresponding readjustment of the pressure-roller has to be made.

At opposite sides of the support D of the 130 knife-head are rigidly attached two racks R, which extend in backward direction at both

sides of the bed-plate, said racks being engaged by means of pinions R' on a driving-shaft S, which is either set in motion by handles operated by hand-power or by means of 5 suitable transmitting gear-wheels from a belt-driven power-shaft, according as the machine has to be operated by hand or power. The machine is further provided with treadles for reversing the motion of the machine when it 10 is arranged as a power-machine, so that the forward and backward travel of the knife-head is produced by the reversing of the motion-transmitting gearing. As this feature is well known in stereotype-shaving machines 15 of this class, it is not illustrated in the drawings nor claimed in this application.

The machine is operated as follows: The stereotype plate or block is placed downward on the bed-plate, its end resting against the 20 work-rest b at the front end of the machine. The knife-head is next adjusted to the proper position, together with its knife and pressure-roller, by the hand-wheel, the gage being first set in position, so that the required size of 25 block is presented to the stop-lugs g' at the upper corners of the knife-head. The machine is then set in motion, so that the knife, with its support, is made to travel forward and backward over the stereotype plate or 30 block, so that the shaving cut is made. This shaving cut is repeated until the stop-lugs g' abut against the lugs on the gages, whereupon the shaving action is completed. The stereotype is then removed and another one 35 placed in position. When the thickness of the stereotype changes, the knife-head has to be adjusted by presenting the corresponding lugs of the gages to the stop-lugs and then repeating the former action. During the 40 shaving action the pressure-roller holds the stereotype firmly in position in the bed-plate, as before described.

The advantages of my improved shaving-machine are—

45 First. That the various sizes of stereotypes can be quickly shaved pica high, block high, or type high, as the adjustment of the knife-head is quickly and accurately accomplished.

Second. The arrangement of the pressure- 50 roller at the rear of the shaving-knife holds the stereotype firmly in position and presents

the same in a better manner to the action of the shaving-knife than heretofore.

Third. By the convenient adjustment of the knife-head and pressure-roller all the parts 55 can be individually adjusted as required.

Having thus described my invention, I claim as new and desire to secure by Letters Patent—

1. In a stereotype-shaving machine, the 60 combination, with the support, of a knife-head guided on the same, a knife on said knife-head, adjustable gages on said support adapted to arrest the knife-head in its downward motion, and means for moving said 65 knife-head along the support until arrested by the gages, substantially as set forth.

2. In a stereotype-shaving machine, the 70 combination, with the support, of a knife-head guided on the same, pivoted gages on said support, said gages being provided with lugs of different sizes, a knife supported on the face of the knife-head, stop-lugs at the ends of the knife-head, and means for raising or lowering the knife-head until the same 75 is arrested by contact with the stop-lugs of the gages, substantially as set forth.

3. In a stereotype-shaving machine, the 80 combination of a reciprocating support, a knife-head guided on said support, a knife on said knife-head, and a yielding roller located back of the knife and below the edge of the same, substantially as set forth.

4. In a stereotype-shaving machine, the 85 combination, with a reciprocating support, a knife-head supported on said support, a knife attached to said knife-head, a spring-pressed roller located back of the knife-head and below the edge of the same, guide-boxes for the shanks of the roller-bearings, and screw-splines for adjusting said shanks so as to adjust 90 the roller to the required position relatively to the edge of the shaving-knife, substantially as set forth.

In testimony that I claim the foregoing as 95 my invention I have signed my name in presence of two subscribing witnesses.

FERDINAND WESEL.
